United States Patent Office

Des. 204,824
Patented May 17, 1966

204,824

JUG

James E. Plummer, Toledo, Ohio, assignor to Owens-Illinois, Inc., Toledo, Ohio, a corporation of Ohio

Filed Oct. 23, 1965, Ser. No. 87,861

Term of patent 14 years

(Cl. D58—5)

FIG. 1

FIG. 2

FIG. 3

FIG. 1 is a front elevational view of a jug showing my new design.

FIG. 2 is a side elevational view thereof.

FIG. 3 is a top plan view thereof.

The back is a mirror image of the front.

The characteristic features of this design reside in the configuration shown in full lines on the drawing.

I claim:

The ornamental design for a jug, substantially as shown and described.
